UNITED STATES PATENT OFFICE.

HENRY W. ROBERTS, OF CHEBOYGAN, MICHIGAN.

LOG-ROAD-MAKING MACHINE.

SPECIFICATION forming part of Letters Patent No. 340,680, dated April 27, 1886.

Application filed December 28, 1885. Serial No. 186,909. (No model.)

To all whom it may concern:

Be it known that I, HENRY W. ROBERTS, a citizen of the United States, residing at Cheboygan, in the county of Cheboygan and State of Michigan, have invented certain new and useful Improvements in Log-Road-Making Machines, of which the following is a specification, reference being had therein to the accompanying drawings.

10 My invention relates to a road-making device; and it consists in the construction and arrangement of the parts, which will be more fully hereinafter described, and pointed out in the claims.

15 In sections of the country where logs and lumber are transported in the winter season a road is formed in the snow, along which logs and lumber are drawn. This road often becomes worn through to the ground by continual usage.

20 The object of my invention is to provide means for flushing these roads with water by a suitable vehicle, so that they will again be covered with ice, the construction whereof is simple and durable, and whose accompanying appliances render it convenient and readily used and handled. I attain these objects by the mechanism illustrated in the accompanying drawings, wherein like letters of reference 25 indicate similar parts in the several views, and in which—

25 Figure 1 is a perspective view of my improved road-making device, illustrating one of the ladders in position and the bucket in act of being drawn up. Fig. 2 is an elevation of one of the ends, illustrating the ladders in position and the manner of hoisting the buckets. Fig. 3 is a top plan view of my improved 30 machine with the ladders, buckets, and guy-ropes removed. Fig. 4 is a longitudinal vertical section of the bed.

35 A indicates a box, which has sides a^1 , ends a^2 , bottom a^3 , and top covers, a^4 a^5 , which are provided with removable fastening means, 40 as a^6 . This box A is provided with compartments A^1 A^2 and A^3 , which are divided by walls A^4 A^5 , which have suitable apertures, a^7 , in their lower portions, which allow a connection between all of the said compartments. 45 The exterior of the box A, on the sides, top, and bottom, are braces or strengthening beams A^8 , which are mortised and fit into each other,

and have suitable dowel-pins, a^9 , securing the parts in position.

50 On each side of the central compartment, A^3 , guard-rails B B are constructed, which act to guide the buckets into their proper place. These guard-rails B are formed by four posts, b b , extending up from the outside of the sides a a of the box A. These posts b are mortised 55 in the uppermost portions, and have cross-bars b^1 b^2 set therein. Inclined braces b^3 b^4 run from the uppermost parts of the posts b b to about the center of the top portion of the box.

60 In the compartment A^3 , on each side of the inside portion thereof, are vertical rods A^6 , of wood or other material, which extend down through the bottom of the box A, filling apertures a^6 , through which the water is allowed 65 to run when the said rods A^6 are withdrawn.

65 Extending upward on an incline from each side of the top of the central opening of compartment A^3 are strips b^5 b^6 , which form a peak, and have strips b^7 b^8 binding upon their uppermost uniting edges. These inclined 70 rafters form a foundation for the buckets to rest upon while filling the box with water. To one side of these rafters, and extending down to and resting upon the bottom of the 75 box, is a post, C, which extends some distance above the box, and has an eye, c, secured to the uppermost portion thereof, which engages the hooks c' of two sheaves or pulleys, C' C'. These pulleys C' C' have guy-ropes C' C' passing therethrough, which at one end pass over the front of the box A when in operation, and at their other ends are secured to loops d' of bails d , which are pivoted at or about the center of the sides of buckets D. These buckets 80 D have suitable valves, d^1 , in the bottoms thereof, which open inwardly, so as to admit 85 of the inflow of water and prevent the outflow of the same while filling the buckets.

90 Suitable ladders, E E, are adapted to engage with the sides of the box A, and up which the buckets D D are drawn between the side bars thereof. When these ladders are not in use, they are adapted to be drawn up and thrown over the guard-rails B B, and 95 the buckets D D also drawn up and rested on the ladders E E. The guy-ropes C' C' are wound around the posts C.

100 The box A is mounted upon and secured to

longitudinal beams F F, which beams are secured to suitable bolsters, F' F', which in turn are connected to cross-beams F² F². The ends of the cross-beams F² F² are engaged by the 5 metal straps f f, secured to the sleigh-shoes G G. These sleigh-shoes G G are connected at their inside ends by cross-braces g g, which are united by the tie-rods g' g', which keep the one or the other of the said shoes from 10 having a different movement from the remaining one, thus giving a relative movement to both. These shoes G G are suitably braced on their sides, and on the inside ends of each of the shoes eyes g² g² are secured, which are 15 engaged by the hooks h h, attached to the ends of the pole-tree H'. A pole, H, is secured to the central portion of the pole-tree H', said tree having a link, h', attached to the upper central surface thereof, to which a suitable 20 whiffletree may be attached. This pole H and tree H', with their hooks h h, are removably attached to the shoes G, and are adapted to be interchanged from one end to the other, so as to avoid turning the entire device, which 25 in many instances might be inconvenient.

The construction of my improved device having been carefully followed out, as illustrated in the drawings, the operation of filling with and distributing water from the box will 30 be as follows: The vehicle entire having been drawn to a suitable place to obtain water, the ladders E E are adjusted on the sides a a of the box A, adjacent to the central compartment, A³. The buckets D D are then lowered 35 by means of the guy-ropes C² C² down the ladders E E and filled, as heretofore described. When the said buckets D D have become filled, they are drawn up the ladders E E, and their contents dumped into the central compartment, A³. The water which is put into 40 this compartment also flows through the apertures a' in the partitions A⁴ A⁴ into the compartments A² A², and as the compartment A³ is gradually filled the water flowing into the 45 compartments A² A² will by a well-known law of physics seek the same level, and this operation continues until the three compartments A² A² and A³ are filled. The ladders E E and buckets D D are now placed in position on the 50 top of the guard-rails B B and the guy-ropes C² C² wound around the post C. The entire vehicle is then drawn to the place where it is desired to make the road, and the rods A⁶ are withdrawn from their apertures a⁶, and the 55 water allowed to flow through the same between the two sets of shoes G G on the ground and allowed to freeze, thus covering the exposed earth or road with ice. When the water has all been distributed, the rods A⁶ are replaced, 60 and the vehicle is again drawn to a suitable place for replenishing the supply of water. In some instances only one bucket can be used at a time; but, as illustrated in Fig. 2, I have shown how the box A can be filled from two 65 sides at the same time when the entire vehicle is so situated that they can thus be used.

By the construction of the combined pivot-

ally-connected shoes, suitably braced, as described, an equalization of the draft is obtained, and at the same time an easy means of turning 70 the vehicle is provided.

By constructing the pole and tree adapted to be attached to either side of the vehicle, the transportation of the vehicle is rendered more convenient and of comparatively easy management. 75

Suitable power may be applied to the guy-ropes to aid in drawing up the buckets and aid in rapidly filling the compartments.

This device is adapted to be used in making 80 roads in lumbering sections of the country, whether inclined or level, as the machine is equally efficient in its working on either.

It is obvious that many minor details of construction could be made and substituted for 85 those shown and described without in the least departing from the nature and principle of my invention.

Having thus described my invention, what I claim as new, and desire to secure by Letters 90 Patent, is—

1. In a road-making machine, the combination of a box divided into suitably-connected compartments, buckets operated by guy-ropes for filling the same with water, openings in 95 the bottom of the central compartment for distributing the water, and means for transporting the same from one position to another, substantially as described.

2. In a road-making machine, the combination of a box divided into suitably-connected compartments, buckets operated by guy-ropes for filling the same with water, openings in the bottom of the central compartment for distributing the water, ladders adapted to rest 100 against the sides of said box and up which the buckets are drawn, and a double set of sleigh-shoes pivotally connected to the said box, substantially as described.

3. In a log-road-making machine, the combination of a box divided into suitable compartments, apertures in the divisional partitions connecting said compartments, suitable guard-rails and inclined rests mounted upon the top of the box, buckets operated by guy-ropes 115 passing through pulleys connected to a vertical post adapted to fill the compartments with water, openings in the bottom of the central compartment for distributing the water, ladders adapted to be set at an incline against the 120 sides of the box and up and down which the buckets are operated, and united sleigh-shoes having a relative movement and upon which the box is mounted, substantially as described.

4. In a log-road-making machine, the combination of the box divided into suitable compartments, apertures for connecting the same, buckets having suitable valves for filling the central compartment with water, openings in the bottom of the central compartment adapted 125 to distribute the water, ladders adapted to rest against the sides of the box, up and down which the buckets pass, suitable guy-ropes for operating these buckets, removable rods clos- 130

ing apertures in the bottom of the box, which allow the water to flow out thereof when open, and combined pivotal sleigh-shoes or bob-sleighs having a relative movement and adapted to run either direction, substantially as described.

5. In a log-road-making machine, the combination of a box divided into a series of compartments, the central one of which is filled with water, apertures connecting these compartments and allowing the water to run into the other divisions, means for filling the compartments with water and allowing it to flow out, and combined relatively-moving sleigh-shoes on which the box is mounted adapted to have the pole and tree attached to either end, substantially as described.

15 6. In a log-road-making machine, the combi-

nation of the box A, divided into compartments A² A² and A³, buckets D, operated by guy-ropes C² C², and sliding up and down the ladders E E, adapted to fill the central compartment, A³, with water, and openings a⁶ in the bottom thereof, to allow the water to flow out, connecting the compartments, suitable 25 guard-rails, B, on the top of the box A, and pivotal sleigh-shoes or bob-sleighs G G, suitably braced and united and adapted to run from either end upon which the box A is mounted, substantially as described.

In testimony whereof I affix my signature in presence of two witnesses.
